UNITED STATES PATENT OFFICE.

WILLIAM R. BEATTY, OF HAMMOND, INDIANA.

LONG-STROKE VERTICAL-TYPE PRESS.

1,406,334.

Specification of Letters Patent. Patented Feb. 14, 1922.

Application filed May 28, 1921. Serial No. 473,489.

To all whom it may concern:

Be it known that I, WILLIAM R. BEATTY, a citizen of the United States, residing at Hammond, in the county of Lake and State 5 of Indiana, have invented certain new and useful Improvements in Long-Stroke Vertical-Type Presses, of which the following is a specification, reference being had therein to the accompanying drawings.

10 This invention relates to a long-stroke vertical-type press, and the object of the invention is the construction of a machine in the class of presser or bulldozers, which comprises a minimum of parts, and which 15 is simple and efficient in operation, and in which press the power is exerted through a pulling instead of a compression motion. With this and other objects in view, my 20 invention comprises certain novel combinations, constructions and arrangements of parts as will be hereinafter described, illustrated in the accompanying drawings, and more particularly pointed out in the appended claims.

25 In the drawings:

Figure 1 is a view, in side elevation, partly in section, of a long-stroke vertical-type press, constructed in accordance with the present invention, while

30 Figure 2 is an end view of the press, showing the adjusting device partly in section.

Figure 3 is a view, taken on line 3—3, Fig. 1, and looking in the direction of the arrows, and showing some of the parts in 35 section.

Figure 4 is a bottom plan view of the mechanism with the clutch structure shown assembled with the main part of the press.

Figure 5 is a diagram of the press, showing the lower position of the movable ram 40 or die-holder, while

Figure 6 is also a diagram, showing the ram or die-holder in its upper or highest position.

45 Referring to the drawings by numerals, 1 designates the frame of the press, including the horizontal table or stationary die-holder 2, the vertical guide housings 3, and the connecting top arch 4.

50 A movable ram or die-holder 5 is slidably mounted, at its ends, in the vertical guide housings 3. A counterbalance cylinder 6 is mounted on the top arch 4, and connected to the piston rod 7, of cylinder 6, is a cross 55 bar 8. A rod 9 is in the middle of the ram or die-holder 5, and links 10 are connected,

at their ends, to bar 8 and rod 9. A pipe 11 is connected at one end to cylinder 6 and its other end is connected to an air tank (not shown); when the die-holder 5 moves upwardly to its highest position (Fig. 6) upon the frame, air from the tank will rush through pipe 11 into the tank under its piston, and if the air is under pressure, it will assist in raising the die-holder 5; when the die-holder 5 is lowered, as shown in Fig. 5, the air in cylinder 6 will be forced through pipe 11 to the tank (not shown), the air in cylinder 6 acting as a cushion, and the pressure in the tank can be maintained, 60 by the operator, sufficient to counterbalance the movable ram or die-holder 5, so that the raising (Fig. 6) of said movable ram or die-holder will not necessarily require considerable power.

To operate the movable ram or die-holder, a primary shaft 12 is mounted upon the lower portion of frame 1, and near each end is secured primary gears 13. An intermediate shaft 14 is journaled upon the frame, 75 and a small cog or gear 15 is secured to the shaft and meshes with the primary gear 13 (Fig. 2). A driving gear 16, and a reverse gear 17 (Fig. 4) are mounted upon shaft 14. A motor drive shaft 18 is supported 80 contiguous to intermediate shaft 14, and this shaft 18 is provided with gear 19 meshing with gear 16, and gear 20 meshes with an idler gear (not shown), which in turn meshes with gear 17. A forward clutch 21 85 and a reverse clutch 22 is slidably mounted upon drive shaft 18, and by swinging lever 23 in one direction, the forward clutch will be operated to drive the machine in one direction, and upon swinging lever 23 in a 90 reverse direction the reverse clutch 22 will be operated to cause the machine movement to be reversed. When power is imparted to the machine, the primary gears 13 will be rotated, thereby moving the connecting rods 100 24 in a vertical plane; these rods are connected, at 25, to the primary gears 13, and their upper ends are pivotally connected, at 26, in bifurcated extensions 27 of the threaded bolts 28; said bolts 28 are mounted in the 105 ends of the movable ram or die-holder, and on these bolts are mounted adjusting nuts or worm-sleeves 29; these nuts or sleeves 29 have worm-threads on their outer surface, meshing with the horizontal worms 30, 110 which worms are fastened to the operating rod 31 that extends through the die-holder

5, and upon the ends of which rod are hand-wheels 32. By rotating the rod 31, at either end of the machine, the "take-up" or adjusting devices for the connecting rods, 24, will 5 be operated. By means of these two adjusting devices at the ends of the movable ram or die-holder, any unnecessary slack between dies can be removed, or if the nature of the work requires, the available die space 10 may be increased or decreased at will.

It is to be understood that on, or attached to, the stationary die-holder 2 and movable die-holder 5, are placed dies or devices to be used in the work.

15 When the work is placed between the stationary die-holder 2 and the movable die-holder 5 and the machine started for bringing die-holder 5 downward, with a pulling action, will cause the downward movement 20 of die-holder 5, which is a very efficient result, not heretofore obtained in the long-stroke vertical-type press. Further, I have provided adjusting means for connecting the connecting rods to the movable die-holder, whereby any slack can be taken up, 25 or the distance of the movable die-holder with respect to the stationary die-holder, can be varied at the will of the operator, and I have also provided, in a vertical-type press 30 of the kind described, a counterbalancing means, which counterbalancing means includes the cylinder 6 and its coordinate parts.

The function of parts 28, 29, 30 and 31 35 is to form a connection between ram 5 and connecting rods 24. They also serve to increase or decrease the die space between the ram 5 and table or die-holder 2. By rotating the shaft 31, carrying the worms 30, 40 which in turn rotates adjusting nuts or sleeves 29, this will move the ram or die-holder 5, up or down as desired to suit various thicknesses of dies. The lower part of bolt 28 is supported by the walls of die-holder 5, as at "A," and the upper part as 45 at "B."

The function of the air cylinder 6 is to counterbalance the ram and attached parts, preventing them from descending of their 50 own weight when the press is at rest.

I believe that my machine is the only one in which power is applied to original high speed shafting and transmitted to the movable ram or die-holder through a plurality 55 of shafts and clutches through certain design of gearing and from there through connecting rods.

While I have described the preferred embodiment of my invention, and have illustrated the same in the accompanying drawings, certain minor changes or alterations 60 may appear to one skilled in the art to which this invention relates, during the extensive manufacture of the same and I, 65 therefore, reserve the right to make such

alterations or changes as shall fairly fall within the scope of the appended claims.

What I claim is:

1. In a long-stroke vertical-type press, the combination of a frame provided with a stationary die-holder, a vertically movable die-holder on said frame, a shaft provided with gears on said frame, connecting rods connected to said gears, and adjusting devices connecting the connecting rods and the vertically movable die-holder. 70

2. In a long-stroke vertical-type press, the combination of a frame including a stationary die-holder and guide housings, a movable die-holder mounted in said housings, a driving shaft on said frame, and means adjustably connecting the ends of the movable die-holder to said driving shaft. 80

3. In a long-stroke vertical-type press, the combination of a frame provided with open guide housings, said frame provided with a stationary die-holder between said housings, a vertically movable die-holder between and traveling in said open housings, and driving means below said housings and connected to 90 the vertically movable die-holder near its ends. 85

4. In a long-stroke vertical-type press, the combination of a frame provided with a stationary die-holder, a movable die-holder on 95 said frame, a counterbalance cylinder on said frame, a piston in said cylinder, means connecting said piston and the central portion of the movable die-holder, and means for moving the movable die-holder upon the 100 frame. 95

5. In a long-stroke vertical-type press, the combination of a frame provided with a stationary die-holder, a movable die-holder on 105 said frame, a shaft on said frame, gears fastened to said shaft, connecting rods fastened at their lower ends to said gears, threaded bolts provided with bifurcated extensions adjustably mounted in said movable die-holder, said connecting rods pivotally secured within said bifurcated extensions, worm-sleeves in the movable die-holder and surrounding said threaded bolts, horizontal worm-sleeves in the movable die-holder meshing with the worm-sleeves on said bolts, a rod extending through said horizontal worm-sleeves and fastened thereto, and hand-wheels on the ends of said rod. 115

6. In a long-stroke vertical-type press, the combination of a frame provided with a stationary die-holder, a movable die-holder on 120 said frame, a shaft on said frame, connecting rods and means connecting said rods to said shaft, and adjusting devices on the movable die-holder and connected to said connecting rods. 125

7. In a long-stroke vertical-type press, the combination of a vertical frame provided with a horizontal, stationary die-holder and with guide housings, a vertically movable 130

die-holder having its ends in said guide housings, movable bolts in said guide housings, means for moving said bolts, a driving shaft on said frame, and means connecting 5 said movable bolts on said driving shaft for operating the movable die-holder and imparting a pulling movement to the same toward the stationary die-holder.

8. In a long-stroke vertical-type press, the 10 combination of a frame including guide housings and a stationary die-holder, a vertically movable die-holder in said guide housings, a shaft on said frame, gears secured to said shaft, connecting rods connected to said gears, and means on the ends 15 of said vertically movable die-holder within

the guide housings and adjustably connecting the connecting rods to the movable die-holder.

9. In a long-stroke vertical-type press, the 20 combination of a frame provided with a stationary die-holder, a movable die-holder on said frame, a cylinder on said frame provided with a piston rod, a bar connected to said piston rod, a rod extending through 25 said movable die-holder, links connecting the ends of said bar and the ends of the last-mentioned rod, and means for supplying pressure to the cylinder.

In testimony whereof I hereunto affix my 30 signature.

WILLIAM R. BEATTY.
